2,506,493

GARMENT

Mabel A. Elstrom, Minneapolis, and Ruth M. Pauly, Medicine Lake, Minn., assignors to Alden Wonderall Company, Minneapolis, Minn., a corporation of Minnesota

Application December 2, 1946, Serial No. 713,524

1 Claim. (Cl. 2-227)

1

This invention relates to overall type garments and more particularly to overall type garments in the size ranges used by children.

It is an object of the invention to provide an improved overall type garment of sturdy, yet economical construction capable of being manufactured without wasting material. It is also an object of the invention to provide a garment which readily fits the user's figure and one in which the waist line may be readily adjusted over a wide range of sizes. It is a further object of the invention to provide a garment of improved style and cut.

Other and further objects of the invention are those inherent in the apparatus herein illustrated, described and claimed.

The invention is illustrated with reference to the drawings in which:

Figure 1 is a rear elevational view showing certain portions of the garment belt unfastened at one side;

Figure 2 is a side elevational view with the belt shown unfastened at one side;

Figure 3 is a side elevational view corresponding to Figure 2 with the belt fastened;

Figure 4 is a side rear elevational view of a youthful figure showing the rear drop seat of the garment unfastened;

Figure 5 is a front elevational view of a slightly modified form of the invention;

Figures 6 and 7 are rear and front elevational views, respectively, of another slightly modified form of the invention.

Throughout the drawings corresponding numerals refer to the same parts.

Referring to the drawings, Figures 1-4, the garment is composed of a front panel 10 which extends from the bottom of the garment leg or cuff, where used, to the waist line 11. If desired, the front panel may extend upwardly above the waist line to form the shoulder straps, as hereinafter described in Figure 5. The front panel (Figures 1-4) which may be composed of right and left parts 10R and 10L, forms the front portion of the right and left legs from the in-seams 12 and 13 to the out-seams 14 and 15. In most instances the front panel is composed of a right and left portion 10R and 10L which are sewed together along a front middle seam from the crotch to the waist line. The rear portion of the garment is composed of a rear panel 20 which likewise may be composed of right and left panel portions 20R and 20L as shown in Figure 1. Where thus composed of two portions, they are sewed together

along the rear middle seam 21 from the crotch 22 to the waist line at 23.

To the right and left front panels 10R and 10L at the side seams of each, there is attached a narrow flat flap 24 and 25 which extends up and serves as the anchor for shoulder straps 26 and 27. The shoulder straps extend upwardly in crossed relationship, as indicated at 28, Figure 4, thence over the shoulders 29 of the wearer and thence downwardly to the upper corners 30 and 31 of the bib 32 or waist. In the event no bib or a rudimentary bib is used, the straps are extended down the front to waist level. Where a bib is used it may be curved off along edges 33 and 34 and terminate at the rear edge of flaps 24 and 25, as indicated at 35 and 36. The shoulder straps 26 and 27 thus extend up from the upper edge of the bib 32 (or from the waist, if no bib is used) and go thence over the shoulders and downwardly to the upper corners of flaps 24 and 25. The shoulder straps 26 and 27 are preferably attached to the bib by means of adjustable (snap) buckles 38 and 39, or they may be extended to the waist where they may be attached by buckles or by sewing. If desired, the panels 10R and 10L may extend upwardly, above seam 11 and thence be shaped off gradually from the sides and middle to form the shoulder straps, as shown in Figure 5, in which case there is desirably no seam in the front at waist level.

The rear panel 20 is provided with a belt at 40 which extends along the upper edge of the rear panel to which it is stitched with darts at 42 and 43 for the purpose of shaping the seat of the garment. The belt extends and forms tab portions 43 and 44 which overlie the junction of the front panel in the areas 45 and 46. The tab portion 43 is provided with spaced snap fastener parts 48 and 49 or with button holes or buckle elements, which cooperate with similarly spaced fastener elements 50 and 51 at the right side. On tab portion 44 there are likewise provided spaced snap fastener parts 52 and 53 or button-holes or buckles, which cooperate with similarly spaced fastener elements 55 and 56. When snap 48 is attached at 50 and 49 at 51, there is provided one position of adjustment but it will readily be appreciated that snap 48 may be attached at 51 and 49 may be attached at 50, thus providing two additional waist line adjustments. Similarly, snaps 52 and 53 may be attached at 55 and 56, respectively, or 53 may be snapped at 55 or 52 snapped at 56, thus providing three additional belt adjustments at the left side. The ultimate number of adjustments provides six

waist line sizes by utilizing only two spaced snaps at the right and left sides. The same effect can be accomplished with spaced buttonholes at 48, 49, 52 and 53 and cooperating underlying buttons at 50, 51, 55 and 56. Buckle elements may be used if desired.

By unfastening both of the tab portions as indicated in Figures 4 and 5, the wearer may readily drop the seat of the garment for removing it or for other obvious purposes.

If desired, the garment structure of Figures 1-4 may be slightly modified as shown in Figure 5, wherein the front panels 60 and 61 compose not only the fore part of the legs, but also extend upwardly as one continuous piece through the belt line and are then curved off at 62, 63, 64 and 65 to form the fore part of the shoulder straps which are of gradually decreased width. The lowermost part of curves 63 and 64, viz. area 66, may be cut either low or high to form a rudimentary bib, no bib or a full bib. The shoulder straps 67 and 68 so formed extend over the shoulders, thence are crossed as at 69 and thence extend downwardly and are fastened to the upper rear corners of the side flaps as described with reference to Figures 1-4. In this instance the shoulder straps are shown non-adjustable, but may easily be altered at their rear point of attachment, or the rear attachment may be by way of buttons, snaps or buckles to allow adjustment.

The waist line of the modification shown in Figure 5 is defined by the belt ends 70 and 73, the end 70 being shown fastened and 73 loosened. These may be supplied with snap fasteners 71 and 72 for belt end 70 and 14-17 inclusive or belt end 11, or with button-buttonhole attachments or buckles. In the garment shown in Figure 5, the front panels 60-61 are sewed at in-seam 78.

The garment of Figures 1-4 may, if desired, be modified slightly to the form shown in Figures 6 and 7 which illustrates a style of garment that is most appropriate for little girls. In Figures 6 and 7 the front leg panels 80 and 81 are fastened together at in-seam 82 and terminate at belt level 83. The same is true of the rear leg panels as in the garment shown in Figures 1-4. Support for the garment is provided by wide shoulder straps 84 and 85 which are fastened side by side at waist level on the front of the garment. From waist level the wide straps diverge upwardly and after passing over the shoulders they continue down at 84R and 85R, and cross and are fastened at waist level partly to the upper edges of the flaps 94 and 95 and partly to the front portions of the garment adjacent the flaps. The right and left out-seams 86 and 87 joining the front and rear leg panels terminate at level 88-89 and are formed with plackets as shown with reference to Figures 1-4, it being noted that flaps 94 and 95 are provided at each side to underline the placket

closure and with the side front portions of the front panels to anchor the wide shoulder straps. From the right and left sides of the rear part 80 of the garment there extends belt ends 91 and 92, the end 92 being shown in fastened closed) condition, whereas belt 91 is in the unfastened (open) condition. The fastening of belt ends 91 and 92 is, in this instance accomplished by a buckle arrangement having a buckle part 93 adjustably positioned on the belt ends 91 and 92, respectively. The buckle parts carry one element 95 of a snap fastener which cooperates with another element on the front of the garment. One such cooperating snap element is shown at 96. In this way the decorative and adjustable effect of the buckle is retained while permitting ready loosening.

As many apparently widely different embodiments of this invention may be made without departing from the spirit and scope thereof, it is to be understood that we do not limit ourselves to the specific embodiments herein except as defined by the appended claim.

What we claim is:

25 A trouser garment composed of front and back panels fastened together to form body and leg portions, the front and back panels being unsecured at the sides in the body portion from the waist line downwardly so as to form side closures, the front panel of the trousers section having an upstanding bib portion, said back panel terminating at substantially the waist line of the garment, shoulder straps of relatively narrow width extending upwardly from said bib portion, one at each side of the bib so as to pass over the shoulders of the wearer and then downwardly in crossed relation at the back, said front panel having narrow vertically extending flaps secured thereto in line with the side seams of the garment and extending at least substantially the 40 depth of the closure, said flaps extending rearwardly a distance not substantially exceeding the width of the shoulder straps, the rear ends of said shoulder straps being permanently fastened at the upper edge of said flaps so as to concentrate the pull of the shoulder straps substantially 45 at the junction of the side seam line and the waist line of the garment.

Certificate of Correction

Patent No. 2,506,493

May 2, 1950

MABEL A. ELSTROM ET AL.

It is hereby certified that errors appear in the printed specification of the above numbered patent requiring correction as follows:

Column 2, line 33, for "darts at 42" read *darts at 41*; column 3, line 39, after the word "sewed" insert *together*;

and that the said Letters Patent should be read with these corrections therein that the same may conform to the record of the case in the Patent Office.

Signed and sealed this 15th day of August, A. D. 1950.
